[57] CLAIM

The ornamental design for a combined key and card holder, as shown and described.

DESCRIPTION

FIG. 1 is a top, front, and right side elevational view of a combined key and card holder showing my new design, the broken-line disclosure of a key and card being for illustrative purposes only and forming no part of the claimed design;

FIG. 2 is an enlarged front elevational view thereof;

FIG. 3 is an enlarged rear elevational view thereof;

FIG. 4 is an enlarged left side elevational view thereof,

the right side being a mirror image of that shown;

FIG. 5 is an enlarged top plan view thereof; and,

FIG. 6 is an enlarged bottom plan view thereof.
